WILLIAM R. ORMES, OF WALTHAM, MASSACHUSETTS, ASSIGNOR TO UNIVERSAL SAFETY TREAD COMPANY, OF BOSTON, MASSACHUSETTS, A CORPORATION OF MASSACHUSETTS.

MACHINE FOR MAKING STAIR-TREADS AND THE LIKE.

1,288,663.

Specification of Letters Patent.

Patented Dec. 24, 1918.

Application filed November 17, 1917. Serial No. 202,675.

To all whom it may concern:

Be it known that I, WILLIAM R. ORMES, of Waltham, in the county of Middlesex and State of Massachusetts, a citizen of the 5 United States, have invented a new and useful Improvement in Machines for Making Stair-Treads and the like, of which the following is a specification.

My invention is particularly adapted for 10 the construction of plates for stair treads of a kind described in a companion application hereto, although it may be otherwise employed. It relates more particularly to means for enabling the blank or plate to be 15 fed and for intermittently feeding the blank.

My invention will be understood by reference to the drawings, in which—

Figure 1 is a side elevation,

Fig. 2 a plan, and

20 Fig. 3 a longitudinal section on line 3—3 of Fig. 2, of a machine embodying my invention.

Figs. 4, 5 and 6 are cross sections showing the dies by which the plate in question is 25 constructed,

Fig. 7 being a cross section of the plate itself.

The plate A comprises rectangular flanges 30 *a* which are died out from the body of the plate by the dies shown in Figs. 4, 5 and 6 and normally stand at substantially right angles thereto, being joined to the plate at one edge, Fig. 7 showing the plate in its reverse position in which it passes from the 35 machine.

The novelty of this plate consists in leaving what I have termed a bridge-piece *a* between the openings from which the flanges have been cut, as described in the said application and as will be understood from Figs. 40 6 and 7.

B is a bed plate suitably supported. C is what may be termed an anvil or die holder suitably shaped and supported and having 45 at its upper end C¹ a recess within which the die member is carried. This die member is made up of a series of recesses *c* which are separated from each other by projecting members *c*¹, *c*² (see Figs. 5 and 6) of different widths, which support the plate during 50 the forming operation, though the novel feature of my machine applies equally to a machine for the making of plates of a dif-

ferent character. The punch member C⁴ is contained in a recessed block C² carried by 55 a reciprocating head C³, being held in place within said block by a screw *c*³. This member comprises a series of punches *c*⁴ of suitable shape and character registering with the recesses *c*. The head is constructed and 60 operated in a manner well known, and hence need not be further described.

D is a stationary work support over which the plate A is fed by means of rolls D¹, D² mounted on shafts D¹¹, D¹². The shaft D¹² 65 carrying the lower roll D² is mounted in bearings in blocks D⁸ supported between uprights D⁴ attached to the bed plate B. The shaft D¹¹ carrying the upper roll D¹ is mounted in sliding blocks D⁵ which slide 70 between the uprights D⁴, the roll D¹ being held against the roll D² by means of springs *d* which engage the blocks D⁵. Screws *d*¹ control the tension of the springs, and eccentric shaft *d*² extending across the machine and operated by a handle *d*³, allows the rolls to be separated in order to receive a fresh piece of work in a way well known. Each shaft D¹¹, D¹² carries at each end a gear F¹, F², the gears on the two shafts being 75 in mesh.

Between the feed rolls D¹, D² and the punch and die members and normally on a level with the table D there is located a table E, which is hinged at *e* to supports E¹ 80 mounted one on each side of the machine alongside one of the uprights D⁴. This table is provided with lateral guides E² to direct the course of the plate A to the punch.

In order to give the plate A its necessary 90 intermittent feed I provide a ratchet F mounted fast on a shaft *f* which is journaled on extensions D⁶ on one of the uprights D⁴. The ratchet F is operated by a pawl f¹. The shaft *f* also carries fast thereto a gear F³ in mesh with the gear F². The gear F² is fast with the roll D² and meshes with a gear F¹ fast with the roll D¹. Thus the intermittent rotation of the ratchet F will cause the corresponding rotation of the two rolls D¹, 100 D², which will feed the plate A toward the punch.

The pawl f¹ is mounted on an arm F⁴ swinging on the shaft *f*. To a block F⁵ adjustably mounted on the arm F⁴ is connected 105 by the link F⁶ the lever F⁷ pivoted at f² to a

hanger below the table B, the other end of the lever F⁷ being pivotally connected by a link F⁸ to the head C³. Motive power applied to the head C³, therefore, serves not only to operate the head, but also to operate the feed rolls D¹, D² by the gear train, etc. just above described.

In addition to the link F⁸ the reciprocating punch carrier or head C³ carries a link 10 E³ which carries a pin working in a slot in one end of an arm E⁴, the other end of which is mounted on a shaft e¹, supported in bearings e² on opposite sides of the table and carrying arms e⁴ in each of which is mounted a roll e³ which engages the under side of the 15 table E. It will be seen that a portion of the vertical movement of the punch will thus cause the arms e⁴ carrying the rolls e³ to oscillate and raise and lower the free end of 20 the table E, thus lifting and lowering the work carried by the table. In its lower position (see Fig. 3) the work lies on the anvil, C¹, but when the arms e⁴ are in vertical position (see Fig. 1) the rolls e³ lift the free end 25 of the table E and the work from a horizontal plane sufficient to clear the flanges from the die.

In addition, to strip the plate from the punches, I prefer to provide strippers e⁶, 30 which are plates preferably attached to the tops of the guides e⁵ between which the plate is fed. These plates have a space between them sufficient to allow the punch member C⁴ to reciprocate vertically. The upward 35 stroke of the head C³ carries the punches C⁴ above the level of the strippers e⁶ so that the under surface of the strippers will engage the top surface of the plate and the punches will be drawn out of it.

40 To assist in the feeding operation after the plate A has left the feed rolls, I have provided a toothed wheel G the teeth g of which are constructed and spaced to fit into the openings which the punch has made in 45 the plate A. This wheel is located to receive the end of the work after its first end has left the die and to register with its perforations. Motion is given to this toothed wheel G by means of a worm gear G¹ meshing with 50 a corresponding gear G² on the end of a shaft G³ suitably supported and having at its further end a similar worm connection G⁴, G⁵, the latter gear being on the shaft D¹² with the roll D². This construction is such 55 that each movement of the ratchet F will cause a corresponding movement to be given to the toothed wheel G as well as to the feed rolls D¹, D², this movement being such as to bring one of the teeth g of this wheel into 60 register with one of the openings in the plate A.

The purpose of the lifting of the hinged table E is to lift the flanges a of the plate A out of the recesses c in the die so that the 65 plate A may be fed without obstruction.

The purpose of the slotted connection between the parts E³ and E⁴ is to allow lost motion between these parts so that the arms e⁴ will only be given a restricted movement, such only being necessary to lift the flanges 70 out of their recesses.

As the strips of metal, which are intended to be acted upon by the punch, are of considerable length, say ten feet or more, I provide preferably an addition,—a table H— 75 onto which the plate A will be fed as the work of the machine is completed, thus keeping the plate flat, and this table may well have hinged arms H¹ and a link H² connecting said arms under which the plate passes 80 so as to insure its being kept flat and in engagement with the teeth of the wheel G.

While I have shown this machine as constructed to make this particular kind of plate, my invention may be otherwise embodied and adapted to feed other kinds of work, its chief purpose being the provision of means whereby the plate may be lifted during the feeding operation so that the parts struck down from a plate will be lifted 90 during the feeding operation out of the recesses into which they are struck.

While I have shown the preferred form of my invention, it may be otherwise embodied. The position of the table E is immaterial so 95 long as it lifts the work at the proper time and to a proper height to allow the feeding operation to take place.

What I claim as my invention is:—

1. In a punching machine, the combination 100 with a reciprocating punch carrier, of a coöperating die, a support for said die, a stationary stripping device sustained by said support above said die and serving to strip the work from the punch, means for feeding a strip to be punched above said die and beneath said stripping device, a hinged table on which the strip to be punched may rest, and means, operated from said punch carrier, for raising one end of said table to lift the punched strip from the die when it is to be fed forward over the latter.

2. In a punching machine, the combination 105 with a reciprocating punch carrier, of a coöperating die, a support for said die, a stationary stripping device sustained by said support above said die and serving to strip the work from the punch, intermittently rotating rolls for feeding a strip to be punched above said die and beneath said stripping device, a hinged table on which the strip to be punched may rest, means, operated from said punch carrier, for raising one end of 110 said table to lift the punched strip from the die when it is to be fed forward over the latter, and means, also operated from said punch carrier, for intermittently rotating 115 said rolls.

3. In a punching machine, the combination 120 with a reciprocating punch carrier, of 125

- a coöperating die, a support for said die, a stationary stripping device sustained by said support above said die and serving to strip the work from the punch, intermittently rotating rolls for feeding a strip to be punched above said die and beneath said stripping device, a hinged table on which the strip to be punched may rest, means, operated from said punch carrier, for raising one end of 10 said table to lift the punched strip from the die when it is to be fed forward over the latter, means, also operated from said punch carrier, for intermittently rotating said rolls, and a toothed roll, geared to said feeding rolls, for engaging the punched strip to feed the same forward.
4. In a punching machine, the combination with a reciprocating punch carrier, of a coöperating die, a support for said die, a 20 stationary stripping device sustained by said support above said die and serving to strip the work from the punch, intermittently rotating rolls for feeding a strip to be punched above said die and beneath said stripping device, a hinged table on which the strip to be punched may rest, means, operated from said punch carrier, for raising one end of 25 said table to lift the punched strip from the die when it is to be fed forward over the latter, means, also operated from said punch carrier, for intermittently rotating said rolls, a toothed roll, geared to said feeding rolls, for engaging the punched strip to feed the same forward, a second table serving to
- support the punched strip, hinged arms on 35 said table, and a link connecting said arms and serving to hold said punched strip down in engagement with said toothed feeding roll.
5. In a punching machine, the combination with a reciprocating punch carrier and punch and a coöperating die, a die holder, a hinged work-supporting table adjacent said die holder, pivoted arms carrying rolls on 40 which the free end of said table rests, a lever for operating said arms to lift the free end of said table at intervals to raise the punch work from the die, and means, connected to said punch carrier, for operating 45 said lever.
6. A machine of the kind described comprising a reciprocating punch, a die located to coöperate therewith, a feeding mechanism, means connected to said punch whereby said feeding mechanism may be intermittently operated, a stationary table to coöperate with said feeding mechanism to support the work before and after its engagement by said feeding mechanism, an oscillatory table also connected to said punch to 50 be intermittently oscillated thereby and located in proximity to said die whereby it may lift the finished work therefrom, a toothed wheel adapted to engage the punched portion of the work, and means operated by 55 said punch whereby said wheel may be rotated intermittently.

WILLIAM R. ORMES.
